H. L. FISCHER

PENCIL CLIP

Filed Nov. 22, 1920

Inventor:

H. L. Fischer

UNITED STATES PATENT OFFICE.

HOWARD L. FISCHER, OF ST. PAUL, MINNESOTA, ASSIGNOR TO BROWN & BIGELOW,
OF ST. PAUL, MINNESOTA, A CORPORATION OF MINNESOTA.

PENCIL CLIP.

Application filed November 22, 1920. Serial No. 425,819.

To all whom it may concern:

Be it known that I, HOWARD L. FISCHER, a citizen of the United States of America, residing at St. Paul, in the county of Ramsey and State of Minnesota, have invented 55 certain new and useful Improvements in Pencil Clips, of which the following is a specification.

My invention relates to a pencil clip the primary feature of which is in a clip which 10 is removable from the pencil barrel for repairing or replacing the same and the design of which is such as not to detract from the general symmetrical neat appearance of 15 the pencil.

In mechanical pencils where metal barrels are used for the casing where a high polish or engraved surface is formed on the casing and particularly where gold and silver casings are used it is highly desirable 20 to have a holding clip which can be easily attached without injuring the outer surface of the casing and also readily removed in a particular manner, but not apt to accidentally 25 come off of the casing when the same is in use.

The invention provides a clip formed so as to be held on the pencil casing under 30 spring tension, the free or pocket engaging end of the clip having a tendency to increase the spring tension adapted to hold the clip to the barrel when the same is engaging the pocket of the user.

The invention further includes means for 35 holding the clip against longitudinal or transverse movement when in place on the pencil casing and leaving the inside diameter of a uniform size without any parts projecting into the casing to leave the same 40 free to receive the operating mechanism.

While the construction of my clip is designed primarily to be attached to a casing of a mechanical pencil wherein the operating mechanism is freely removable the 45 same is accordingly well adapted to be used with any design of pencil or any casing where a holding clip is used to attach the pencil or article to the pocket of the user so that it will not be apt to be lost or fall out.

It is also a feature of the invention to 50 provide a clip designed wherein the attaching means does not encircle the barrel, but

extends longitudinally so as to attach the same to the side of the casing or barrel with a portion of the casing or barrel embossed and projecting centrally into the head of the 55 clip to provide a very neat attractive appearance.

In the drawings forming part of this specification:

Figure 1 is a perspective view of my clip attached to a pencil casing or barrel and a portion of which is broken away.

Figure 2 is a central longitudinal section on the line 2—2 of Figure 1.

Figure 3 is a cross section on the line 3—3 of Figure 2.

Figure 4 illustrates a portion of the barrel or casing before the clip is attached thereto.

Figure 5 is a perspective view of the clip separated from the barrel.

Figure 6 illustrates the clip in the position it assumes when being attached to the barrel.

The pencil casing A, only a portion of which is shown, is of any suitable design having a thin wall 10 with a hollow central chamber 11. The wall 10 of the casing or barrel A is formed with an opening 12 and 80 pierced or sheared at 13 at a place on the barrel where it is desired to attach the holding clip B. The portion between the opening 12 and the opening 13 is embossed to project from the outer surface of the casing A to form an embossed portion 14 which 85 extends longitudinally and of a width approximately the same as the width of the opening 12 and the pierced opening 13.

In piercing the barrel A at 13 a locking shoulder is formed by the edge 15 at one end of the embossed portion while the shoulder 16 is formed at the other end adjacent the opening 12.

The clip B is formed from a single piece 90 of sheet material with a head portion 17 and an engaging finger 18. After the clip is blanked out from the sheet material it is formed with the head portion 17 having a curve to simulate the curve or outer shape 100 of the casing A in transverse cross section and the finger 18 is formed to curve upward from the head 17 and longitudinally dished to stiffen and strengthen the same.

The head 17 of the clip B is cut out centrally to form an engaging tongue 19 which is bent to extend parallel to the sides 20 of the head and is adapted to enter the opening 12 in attaching the clip to the pencil barrel so as to engage the inner surface of the embossed portion 14. When the clip B is formed the head portion 17 extends at an angle to the finger 18 so that when the clip 10 is laid on the barrel with the tongue 19 directly above the opening 12 by exerting pressure in the direction of the arrow 21 until the tongue 19 enters the opening 12 and then while in this depressed position 15 the clip is forced in the direction of the arrow 22, the tongue 19 will engage beneath the embossed portion 14 and the upper transverse side 23 will snap over the shoulder 15 to lock the clip B in place on the barrel A. The free end 24 of the finger 18 engages the surface of the barrel with sufficient spring tension to hold the side 23 in close engagement with the surface of the barrel or casing A directly adjacent and 20 against the shoulder 15. The clip B is formed of spring material to give sufficient resiliency to the finger 18 to allow it to be forced over the edge of a person's pocket without distorting its shape. 25 The embossed portion 14 engages the inner edges of the sides 20 and the end 23 while the shoulder 25 formed at the base of the tongue 19 engages the shoulder 16. The ends and sides of the embossed portion 14 30 serve as shoulders to assist in holding the clip B against free transverse or longitudinal movement.

To remove the clip B from the casing the side 23 is raised above the shoulder 15 by 40 inserting a thin instrument under the edge of the same and prying upward in a direction toward the end 24 of the clip. When the side 23 is elevated above the shoulder 15 the clip will slide easily off of the embossed portion 14 and release the tongue 19. The tongue 19 lies in a recess 26 and against the inner surface of the embossed portion 14 out of the chamber 11 to leave a free passage for the reception of the operating mechanism or inner parts of the pencil which are not illustrated in the drawing.

The use of mechanical pencils has recently 55 become very extensive and it has been found that the attaching clips generally used thereon are very apt to become bent, broken or injured in a manner so as not to properly hold the pencil. Many times it is necessary to send the pencils back to the factory to be repaired when the clips get out of order. With my construction the dealer can readily 60 remove the old clip or the remaining portions thereof and attach a new clip in a very short time without any material inconvenience to the user of the pencil.

65 For these reasons the construction and

design of my clip are very important and particularly owing to the fact that while the clip can be readily removed by raising the side 23 out of engagement with the shoulder 15 yet in use the clip will not come off by accident or have a tendency to become loose, particularly as it is held by spring tension locked to the casing or barrel.

In accordance with the patent statutes, I have described the principles of operation 75 of my invention, together with the structure which I now consider to represent the best embodiment thereof, but I desire to have it understood that the drawings are only illustrative and that the invention can be carried out by other means and applied to uses other than those set forth within the scope of the following claims.

What I claim is:

1. A clip in combination with a pencil 85 casing, a spring engaging arm formed on said clip, an opening formed in said clip, an embossed portion in said casing adapted to fit said opening, a holding tongue adapted to engage said casing and a locking shoulder adapted to lock said tongue and clip to said casing when said embossed portion enters said opening to hold said clip against longitudinal or transverse movement.

2. A pencil attaching means comprising, 95 a casing, openings formed in said casing, an embossed portion formed between said openings, a member formed from spring material having an engaging finger, an opening formed in said member adapted to engage the sides of said embossed portion and a locking tongue adapted to removably lock said member into engagement with said embossed portion, to hold said member against longitudinal or transverse play.

105 3. A holding clip in combination with a pencil casing, an outwardly embossed portion formed on said casing, a shoulder formed on either end of said embossed portion, a spring clip having an opening adapted to fit about the sides of said embossed portion, a tongue formed on said clip and an opening formed in said casing adapted to freely receive said tongue to allow said clip to be moved longitudinally and placed 110 into engagement with said shoulders and embossed portion to lock said clip to said casing under spring tension.

115 4. An attaching clip in combination with a pencil casing, comprising a spring member formed from a single piece of material, an opening formed in one end of said member, a tongue projecting into said opening depressed into a plane below said opening, an embossed portion formed on said casing adapted to fit said opening in said member, an opening adapted to receive said tongue 120 when said member is pressed into engagement with said casing, and shoulders formed by the sides of said embossed portion adapt- 125 ed to receive said tongue when said member is pressed into engagement with said casing.

ed to lock said member against longitudinal or transverse movement by engaging with the edges of said opening in said member.

5. A holding clip in combination with a barrel, an outwardly projecting embossed portion formed on one side of said barrel, a resilient member having an engaging finger

on one end and a head portion on the other end and means formed in said head portion adapted to snap over said embossed portion 10 to engage and disengage said embossed portion to attach said member to said barrel.

St. Paul, Minnesota, November 12th, 1920.

HOWARD L. FISCHER.
